No. 618,237.

Patented Jan. 24, 1899.

J. H. SAUNDERS & M. F. PARHAM.
FERTILIZER DISTRIBUTER.

(Application filed Aug. 26, 1898.)

(No Model.)

UNITED STATES PATENT OFFICE.

JOSEPH HUBERD SAUNDERS AND MEDACUS FILMORE PARHAM, OF ROCKY MOUNT, NORTH CAROLINA.

FERTILIZER-DISTRIBUTER.

SPECIFICATION forming part of Letters Patent No. 618,237, dated January 24, 1899.

Application filed August 26, 1898. Serial No. 689,576. (No model.)

To all whom it may concern:

Be it known that we, JOSEPH HUBERD SAUNDERS and MEDACUS FILMORE PARHAM, of Rocky Mount, in the county of Edgecombe, 5 and State of North Carolina, have invented certain new and useful Improvements in Fertilizer-Distributors; and we do hereby declare the following to be a full, clear, and exact description of the invention, such as will enable others skilled in the art to which it 10 pertains to make and use the same.

This invention contemplates certain new and useful improvements in fertilizer-distributors, relating more particularly to that 15 class employed in fertilizing tobacco; and it has for its object the production of a machine of this character which will be exceedingly simple and inexpensive in construction and efficient and positive in operation.

20 The invention will be hereinafter fully set forth, and particularly pointed out in the claims.

In the accompanying drawings, Figure 1 is 25 a view in perspective illustrating our improved fertilizer-distributer. Fig. 2 is a rear elevation. Fig. 3 is a longitudinal sectional view on line 3 3, Fig. 1.

Referring to the drawings, A designates the supporting-frame, comprising two parallel 30 longitudinal side bars a , united by cross-bars a' . The handle-bars a^2 are secured at their forward ends to bars a , said handle-bars being supported by brace-rods a^3 , secured to the rear cross-bar a' . The brace-rods a^3 are connected at their lower ends by an approximately inverted-U-shape member a^4 .

B designates the hopper as an entirety. The same comprises an upper receptacle b , provided with lower shoulders b' , against which 40 are designed to fit opposite metallic plates b^2 , suitable means being provided for securing said plates to said receptacle. Rods or bolts b^3 are passed through coincident holes or openings in said plates and the longitudinal bars of frame A, said rods or bolts serving to support the hopper in position. The inner faces of plates b^2 are provided with opposite coincident shoulders b^4 .

C is a feeding drum or roll keyed to a suitable shaft mounted between plates b^2 , a pinion d being keyed on one end of said shaft

and a sprocket-wheel d' to the other end thereof. Said sprocket-wheel is connected by means of a chain d^2 to a similar sprocket-wheel d^3 on the shaft d^4 of the main drive-shaft D, said shaft being mounted near the forward end of frame A. An agitator d^5 is also mounted between plates b^2 and operated by means of a pinion d^6 , meshing with pinion d . 60

The amount of fertilizer which is fed by the feeding-drum C is governed or regulated by a slide E on the forward side of hopper B and extending down between plates b^2 to a position adjacent said drum. This slide consists of a rectangular bar, to the upper end of which is secured a threaded rod or member e , extending through a hole or opening in an arm or bracket e' , extending from the hopper. The adjustment of the slide is accomplished by means of upper and lower nuts e^2 e^3 , working on said rod. The sliding bar is maintained in its relative position to the hopper by means of a nutted rod or bolt e^4 , extended through a slot e^5 therein. 75

Extending from the U-shape member a^4 of brace-rods a^3 are two parallel arms f , designed to support the fulcrum-pin of an operating-lever F of a cut-off f' . The latter consists of a flat plate, which is supported by and arranged 80 to slide upon the shoulders of plates b^2 . The arm F is designed to be engaged by a catch f^2 , carried by the hopper, whereby said cut-off may be held as against movement when thrown rearward, so as to open up the lower 85 end of the hopper. Suitable covering devices or plows f^3 depend from the rear end of frame A.

The operation and advantages of our improved cultivator will be at once apparent to 90 those skilled in the art to which it appertains. It will be particularly observed that the same is exceedingly simple and inexpensive in construction and positive in operation and, being composed of but few parts, is not liable 95 to readily get out of order or become deranged.

We claim as our invention—

1. The herein-described fertilizer-distributer, comprising a main supporting-frame, a hopper comprising an upper receptacle and lower parallel plates, rods or bolts passed through said plates and said frame and de- 100

signed to support said hopper, a feed-drum mounted between said plates, an agitator also mounted between said plates adjacent said drum, means for rotating said drum and said 5 agitator, an arm or bracket secured to said hopper, a slide having a slot therein and provided with a threaded member projected through said arm or bracket, nuts working on said threaded member, a nutted rod or bolt 10 secured to said hopper and projecting through the slot in said slide, and a cut-off working between said plates above said drum, substantially as set forth.

2. The herein-described fertilizer-distribu- 15 ter, comprising a main supporting-frame, a hopper comprising an upper receptacle and lower parallel plates, said plates having opposite parallel guides or shoulders, rods or bolts passed through said plates and frame 20 and designed to support said hopper, a feed-drum mounted between said plates, an agitator also mounted between said plates ad-

jacent said drum, means for rotating said drum and agitator, an adjustable bar carried by said hopper, forming a regulator, handle-bars secured to said main frame, brace-rods supporting said handle-bars and united by a central U-shape member, parallel arms projecting from the latter member, a lever fulcrumed between said parallel arms, a cut-off 25 plate resting upon the guides or shoulders of said parallel plates and to which said lever is connected, and a catch carried by said hopper and designed to engage said lever, substantially as set forth. 30

In testimony whereof we have signed this specification in the presence of two subscribing witnesses.

JOSEPH HUBERD SAUNDERS.
MEDACUS FILMORE PARHAM.
